UNITED STATES PATENT OFFICE.

BENJAMIN F. BIGGS, OF LA FAYETTE, INDIANA.

IMPROVEMENT IN PUMP-PISTONS.

Specification forming part of Letters Patent No. 147,890, dated February 24, 1874; application filed January 28, 1874.

To all whom it may concern:

Be it known that I, BENJAMIN F. BIGGS, of La Fayette, Indiana, have invented certain new and useful Improvements in Pump-Pistons, of which the following is a specification, reference being had to the accompanying drawings.

The invention relates to the piston of a sucker or pump rod; and consists in providing the side of the piston with an angular aperture, upon the upward-inclining portion of which, and whereat terminates the bore of the piston, is placed a valve of leather or other suitable material, secured so as to work over the upper vent or mouth of the bore, and provided on its upper surface with a valve-block. A flaring annular ring, of leather or other proper substance, is secured about the piston, below the valve, its inner circumference coming in proper juxtaposition to the valve-block, so that, as the piston descends and the valve is thrown open, the block may strike against the annular ring, and thus prevent the valve or block striking the cylinder in which the piston operates.

The object of the invention is to provide a convenient and efficient means of elevating water and fluids.

Figure 1 is a longitudinal vertical section of a device embodying my invention. Fig. 2 is an exterior view, showing certain parts.

A, in the accompanying drawings, is the piston of a pump-rod, provided, as shown, with the aperture or notch B, penetrating to about its vertical axis. The upper face of the notch B inclines downward and inward, the lower upward and inward, the bore D of the piston terminating on the latter face, upon which, between the outer edge of the bore D and the surface of the piston, is secured one edge of the valve E, which extends over the bore, and is provided on its upper surface with the valve-block F, the upper part of which is properly curved toward the hinge of the valve. At a

suitable distance below the notch B is provided the annular shoulder H, upon which is placed the lower edge of the leather ring I, and affixed to the piston A, the shoulder H being of such height that, when the leather is in place, its lower exterior surface shall be about flush with the adjacent parts of the piston. The ring I flares upward and outward, extending upward a suitable distance to receive the blows of the valve-block F when the valve is thrown violently open. The piston is provided with the proper axial aperture L to receive the pump-rod.

The piston A, being inserted in the pump-cylinder with its bore D below, is forced downward, the ring I operating as a guide or packing. When the piston comes in contact with the fluid it descends through it, the valve E opening. The movement of the piston now being reversed, the valve closes, and the ring I filling the space between the piston and the pump-cylinder, the water is carried upward. The water may be elevated by the repeated movement of the piston, which exhausts the air below it, and causes the water to rise until it flows through the valve E. The ring I serves the double purpose of assisting in the elevation of the water and preventing the valve-block F striking violently against the inner surface of the pump-cylinder.

What I claim as my invention, and desire to secure by Letters Patent, is—

The piston A, provided with the valve E, having upon it the valve-block F, in combination with the flared annular leather ring I, arranged to receive the blow of the valve, substantially as shown and described.

In testimony that I claim the foregoing improvement in pump-pistons, as above described, I have hereunto set my hand and seal.

BENJAMIN F. BIGGS. [L. S.]
